UNITED STATES PATENT OFFICE.

GEORG GRABE, OF NIKOLASSEE, NEAR BERLIN, GERMANY, ASSIGNOR TO SIEMENS & HALSKE, A. G., OF BERLIN, GERMANY, A CORPORATION OF GERMANY.

AUTOMATIC TELEPHONE SYSTEM.

1,124,608.

Specification of Letters Patent. Patented Jan. 12, 1915.

Application filed February 8, 1913. Serial No. 747,107.

To all whom it may concern:

Be it known that I, GEORG GRABE, a citizen of the German Empire, and residing at Nikolassee, near Berlin, Germany, have invented certain new and useful Improvements in Automatic Telephone Systems, of which the following is a specification.

My invention relates to automatic telephone systems comprising selectors whose terminals are not arranged according to the decimal system.

In automatic telephone systems the subscribers' lines are divided at the exchange into groups. Each of these groups of subscribers' lines has a number of trunk lines, over which the connections between the subscribers belonging to one group are made to the subscribers belonging to the same or to another group. The number of these trunk lines is only large enough to suffice for the greatest number of conversations carried on simultaneously by the subscribers. If the subscribers' lines are subdivided into small groups, it may happen that the trunk lines of the various groups are very unequally utilized and that very many subscribers in the one group may be speaking while in the other groups almost no speaking whatever takes place. If the subscribers' lines are divided into larger groups, such differences are better equalized and, with an equal total number of trunk lines in the whole of the exchange, a better utilization of the trunks is possible, or the number of terminals necessary to suffice for the largest number of conversations is reduced. As a rule, the subscribers' lines are subdivided into groups of one hundred, and practice has shown that in most cases ten trunk lines per group of subscribers' lines suffice. If, however, the subscribers' lines are subdivided into groups of two hundred, sixteen trunk lines per two hundred subscribers will suffice. If the groups are enlarged it is necessary to use selectors having considerably more terminals than the usual selectors arranged for a 100-group. Since in such selectors the terminals or connection-contacts are no longer arranged in ten rows each of ten contacts, and since the current impulses emitted by the subscriber are issued in accordance with the decimal system, these current impulses cannot be employed for the adjustment of these enlarged

According to my invention I arrange that the trunks which lead to these selectors are connected at several places to the selectors of a previous stage, and are provided with such devices that, according to the adjustment of the selector on the one or other terminal of the trunk line, the selector to be adjusted can make connection with only a portion of the terminals. In this manner by setting the selector of the preceding stage a group of contacts of the line connector can be selected, and the number of contacts or terminals in this group is so small that an adjustment of the selector within this group can be readily effected by the current impulses delivered in accordance with the decimal system.

Several illustrative embodiments of my invention are represented by way of example, in the accompanying drawing, wherein:

Figures 1 to 5 are diagrams for explaining the invention, and Figs. 6 to 9 show four forms of the invention.

Referring to the drawings, Figs. 1 to 3 represent three geometrical figures indicating the distribution of the terminals or contacts of such selectors for more than one hundred connections. The rectangle shown in Fig. 1 is divided into four squares side by side, each of which contains one hundred terminals namely the terminals 1200 to 1299, 2200 to 2299 and so on. In Fig. 2 the squares, each of one hundred terminals, are superposed, and in Fig. 3 they are partly side by side and partly superposed.

The connection LW (Fig. 4) contains four hundred terminals or contacts which can be connected with the junction lines leading to the selector GW_{II}. These four lines form a single trunk but are however connected to four different contacts of the selector GW_{II}, in such manner that by adjusting the selector GW_{II} one of these four lines of the trunk one of the four squares of the connector LW is simultaneously selected.

In Fig. 5 the four lines which lead from the selector GW_{II} to the connector LW are assembled to form one single trunk which divides into four branches only at the end leading to the selector GW_{II}, and these branches lead to the various contacts of the selector GW_{II}. In each of these branches is a device which is indicated by a relay and

which so acts that when the selector GW_{II} is placed on a certain branch, the connector LW is caused to select only in that square of the field of contacts which corresponds to the selected branch.

- 5 The selector may be arranged in any desired manner. It may, for example, comprise four different sets of brushes, which are normally locked, and one of which set 10 is released by occupying one of the branches at the selector GW_{II} , whereupon the brushes in this set are raised and rotated above the field of contacts. It is, however, readily possible to furnish the selector with other 15 devices for permitting it to be adjusted on a portion of the field of contacts before the selection takes place according to decimal system.

- In Fig. 6 the selector W serves, by way 20 of example, for groups of two hundred subscribers, namely for numbers of subscribers from 300 to 499, it may be assumed that the selector has, according to the known Strowger system, a spindle which is vertically dis- 25 placeable and rotatable, so that by raising this spindle, a certain bank of contacts is first found, and by rotating it a definite contact in this bank is selected. The spindle of the selector W carries two sets of brushes 30 a_2, b_2, c_2 and a_3, b_3, c_3 , which are connected with the trunk leading to the selector GW only when the relay P_2 or P_3 respectively is energized. The trunk line from the selector GW is connected at this selector to two dif- 35 ferent sets of contact-pieces g_1 and g .

- This system of connections operates in the following manner:—As soon as the subscriber by using his two keys T_a, T_b has adjusted the selector GW on the contact-pieces 40 g , a circuit is closed from ground, over the resistance w , the winding of the relay P , to the battery. The relay P serves to produce the engaged voltage in the test line of the trunk line leading to the selector W . The subscriber T now uses his keys T_a, T_b to adjust the selector W on the contact-pieces 45 G . These current impulses are transmitted by the relays A and B to those circuits of the selector W which serve for the elevation 50 and rotation of its spindle. As soon as the selector is adjusted on the contact-pieces g , the relay P_2 is energized by way of the back contact of the relay R and the brush c_2 , and connects the brushes a_2, b_2 to the trunk 55 leading from the selector GW . The subscriber T is thereby connected with the subscriber who is connected to the contact-pieces G . Should the subscriber T desire to be connected with subscriber No. 342 who is 60 connected to the contact pieces G_1 he does not adjust the selector GW on the contact-pieces g , but on the contact-pieces g_1 . The relay R is thereby energized, and opens the contact r_1 and closes the contact r_2 . The relay P_2 is thereby disconnected and instead 65

thereof the relay P_3 is connected in circuit, so that when the brush c_3 becomes connected with the test-contact of subscribers No. 342, the relay P_3 is energized, and now connects the brushes a_3, b_3 with the trunk leading 70 from the selector GW .

Fig. 7 represents a similar system, wherein the selected sets of brushes are connected not by means of test relays P_2, P_3 , but by means of the relay R . The subscriber T adjusts the selectors GW_1, GW_{II} in exactly the same manner as described above with reference to Fig. 6. The line which leads from the selector W to the selector GW_{II} is not provided with double connection contacts at 80 the selector GW_{II} but these double connection contacts are already present at the selector GW_1 . According as the selector GW_1 has been adjusted on the contact-pieces which are connected to the upper selector 85 GW_{II} or the lower selector GW_{II} , the relay R remains currentless or is energized. After the selectors GW_1 and GW_{II} have been adjusted, the selector W is adjusted, whereupon the test-relay P connects through the 90 trunk line.

The connection in Fig. 8 differs from those shown in Figs. 6 and 7, in that the selector W comprises only one set of brushes. The trunk line is connected exactly as in 95 Fig. 6 to the contact-pieces g and g_1 of the selector GW , and according as the selector GW is adjusted on the contact-pieces g or g_1 , the relay R remains currentless or is energized. When the relay R remains currentless a completely normal adjustment of the selector W takes place. When, however, the relay R attracts its armature, the relay A becomes first of all alternately currentless and energized owing to the current impulses 100 given by the subscriber, whereas during these impulses the relay B remains energized. Owing to the relay A being intermittently energized, a number of current impulses is set up through the lifting magnet H and the operating contact of the relay A , whereby the spindle of the selector W is raised one bank of contacts. 110

Owing to the relay B being energized the relay U also becomes energized, its circuit 115 being completed at the contact b_1 . As soon as the relay U attracts its armature, it closes a holding circuit over the contact u_3 , whereby it then remains energized when the relay B becomes currentless after the succession of current impulses has been delivered. The relay U , moreover, causes the contacts u_4 and u_2 to be closed, whereby the lifting magnet H is switched out of, and the rotary magnet D switched into circuit. 120 Now as soon as the relay B , becomes currentless after the delivery of the current impulses, the relay F is energized over the contact u_4 , contact r and contact b_2 . The relay F closes the contact f_1 , whereby it then 125

130

remains energized when the relay B shortly thereafter attracts its armature. Owing to relay F being energized, the contact f_2 is made and the rotary magnet D is connected by way of a contact W to an interrupter; the latter delivers ten current impulses in quick succession. The rotary magnet D therefore rotates the spindle of the connector W first of all ten steps. When the subscriber now gives the last succession of impulses corresponding to the unit integer desired, the relay A becomes again alternately currentless and energized, whereby the rotary magnet D again receives the current impulses delivered by the subscriber. If the subscriber sends e. g. five impulses, the rotary magnet D altogether receives fifteen impulses and the selector W is adjusted onto the fifteenth contact of the previously selected bank. In this figure a construction of selector W is assumed comprising ten horizontal banks each of twenty contact-pieces. It will, of course, be readily understood that the field of contacts of the selector may have twenty horizontal banks each of ten contact-pieces. In this case the current impulses delivered over the contact w must flow over the magnet H before the impulses for lifting the spindle of the selector are delivered.

The connection illustrated in Fig. 9 contains a trunk line which is connected to the double contact-pieces g , g_1 of the selector GW. In contradistinction to the other hereinbefore described embodiments of my invention the relay R is however dispensed with. The spindle V of the selector GW carries, in addition to the three brushes a , b , c , a vertically displaceable contact-piece f which is raised in steps simultaneously with the spindle, and after each odd number of steps closes a contact 1, 3, 5, 7. This contact-piece f is, moreover, connected with an impulse sender J, which, when the selector GW is on one of these contacts 1, 3, 5, 7 sends out the ten additional impulses to the next selector W. If the calling subscriber adjusts the selector GW onto an even bank of contacts in which the contact f is open, the next selector G is adjusted in the usual manner. Should, however, the subscriber T so adjust the selector GW that the contact f is made, the selector W seeks in the usual manner a disengaged set of contacts, the relay P then attracting its armature. This relay closes the contact p whereby a current flows from the battery, over the switch-controlling magnet S, the arm s_2 , the interrupter V_1 , the contact p to ground; the magnet S so obtains a current impulse and moves the arms s_1 , s_2 , s_3 of the switch SS into the second position. In this position the relay B_1 becomes energized by way of the contact-arm s_3 , the contact f , and the ground at the subscriber's end T, the

result being that the magnet S is energized by way of the contact b_1 . As soon as the subscriber breaks the connection to ground the relay B_1 becomes currentless, whereby the contact b_1 is opened and the magnet S rendered currentless. The said switch now moves into the third position. In this position a circuit is closed from the battery, over the contact arm s_3 , the interrupter Y and the magnet D_1 to ground. The magnet D_1 now rotates the impulse-sender J once. The arm i of the impulse sender J moves over a number of grounded contacts i_1 , and thereby produces current impulses which flow over the arm s_1 , the brush a of the selector GW, and the relay A, and hence intermittently energize the latter. Therefore the magnet H of the selector W is intermittently energized and the spindle of this selector is raised ten steps. As soon as the arm i has completed one revolution, it closes for a moment the contact i_{11} , the magnet S consequently receiving a current impulse and the switch SS being moved into the fourth position 4, in which position the current impulses sent by the switch J are stopped. Further adjustment of the selector W is now effected in precisely the same manner as described above with reference to the other figures.

I claim:

1. In an automatic telephone exchange, the combination with selectors, of connectors having movable contacts and stationary telephone line contacts arranged in rows in a non-decimal system, trunk lines leading from the movable contacts of said connectors to different contacts of the selectors of a previous stage, and means associated with these selectors and connectors whereby, when the selectors make connection with one of said different contacts of the trunk line, the connector is caused to select only in a part of said telephone line contacts.

2. In an automatic telephone exchange, the combination with selectors, of connectors having movable contacts and stationary telephone line contacts arranged in rows in a non-decimal system, trunk lines leading from the movable contacts of said connectors to different contacts of the selectors of a previous stage, test circuits associated with the trunk lines, and adapted to determine by which of the different contacts of the trunk lines connection is made by the selector, and means associated with these test circuits adapted to cause the connector to select in a part of the telephone line contacts in dependence on the test circuits.

3. In an automatic telephone exchange the combination with selectors and connectors having movable contacts and stationary telephone line contacts arranged in rows, said rows comprising more than ten contacts, and trunk lines leading from the

movable contacts of said connectors to different contacts of the selectors of a previous stage, test circuits associated with the trunk lines and adapted to determine by which of said different terminals of the trunk lines the connection is made by the selector, and means associated with these test circuits adapted to send ten supplementary impulses when the movable part of the connector must make more than ten steps in order to reach the desired contacts.

4. In an automatic telephone exchange the combination with selectors and connectors having movable contacts and stationary telephone line contacts arranged in rows, said rows comprising more than ten contacts, and trunk lines leading from the movable contacts of said connectors to different contacts of the selectors of a previous stage, test circuits associated with the trunk lines and adapted to determine by which of said different terminals of the trunk lines connection is made by the selector, and means associated with said test circuits adapted to send ten supplementary impulses when the movable part of the connector must make more than ten steps in order to reach the desired contacts, said supplementary impulses being sent through the trunk lines, by which connection with the connector is established.

5. In an automatic telephone exchange the combination with selectors and connectors having movable contacts and stationary telephone line contacts arranged in rows, said rows comprising more than ten contacts, trunk lines leading from the movable contacts of said connectors to different contacts of the selectors of a previous stage, test circuits adapted to determine by which of said different terminals of the trunk line connection is made by the selector, and interrupters associated with the test circuits adapted to produce ten supplementary impulses when the movable part of the connector must make more than ten steps in order to reach the desired contacts, said interrupters being associated with that selector whose stationary contacts are connected with the different terminals of the trunk line.

6. In an automatic telephone exchange the combination with selectors and connectors having movable contacts and stationary telephone line contacts arranged in rows, said rows comprising more than ten contacts, the numbers of each hundred of telephone lines being differentiated by digit setting switches operated before operating said connectors, trunk lines leading from the movable contacts of said connectors to different contacts of the selectors of a previous stage, the trunk line contacts of said selectors by which connection is made to different hundreds groups of telephone line

contacts of the same thousands group being arranged in the same group of selectors, trunk lines leading from the movable contacts of said connectors to different contacts of the selectors of a previous stage, test circuits adapted to determine by which of said different terminals of the trunk line connection is made by the selector, and interrupters associated with the test circuits adapted to produce ten supplementary impulses when the movable part of the connector must make more than ten steps in order to reach the desired contacts, said interrupters being associated with that selector whose stationary contacts are connected with the different terminals of the trunk line.

7. In an automatic telephone exchange the combination with selectors and connectors having movable contacts and stationary telephone line contacts arranged in rows, said rows comprising more than ten contacts, each hundred of telephone line contacts having digits in a place higher than the hundreds differing from the other hundreds of telephone line contacts at the same connector, trunk lines leading from the movable contacts of said connectors to different contacts of the selectors of a previous stage, the trunk line contacts of said selectors by which connection is made to different hundreds groups of telephone line contacts of the same thousands group being arranged in the same group of selectors, test circuits adapted to determine by which of said different terminals of the trunk line connection is made by the selector, and interrupters associated with the test circuits adapted to produce ten supplementary impulses when the movable part of the connector must make more than ten steps in order to reach the desired contacts, said interrupters being associated with that selector whose stationary contacts are connected with the different terminals of the trunk line.

8. In an automatic telephone exchange the combination with selectors and connectors having movable contacts and stationary telephone line contacts arranged in rows, said rows comprising more than ten contacts, each hundred of telephone line contacts having digits in a place higher than the hundreds differing from the other hundreds of telephone line contacts at the same connector, trunk lines leading from the movable contacts of said connectors to different contacts of the selectors of a previous stage, the trunk line contacts of said selectors by which connection is made to different hundreds groups of telephone line contacts of the same thousands groups being arranged in the same group of selectors, test circuits adapted to determine by which of said different terminals of the trunk line connec-

tion is made by the selector, said circuits being only at the outgoing end of the trunk line, and interrupters associated with the test circuits adapted to produce ten supplementary impulses when the movable part of the connector must make more than ten steps in order to reach the desired contacts, said interrupters being associated with that selector whose stationary contacts are con-

nected with the different terminals of the trunk line.

In testimony whereof, I have signed my name to this specification in the presence of two witnesses.

GEORG GRABE.
